UNITED STATES PATENT OFFICE.

GEORGE E. COX, OF NIAGARA FALLS, NEW YORK, ASSIGNOR TO AMERICAN CYANAMID COMPANY, OF NEW YORK, N. Y., A CORPORATION OF MAINE.

PROCESS AND APPARATUS FOR MAKING CALCIUM CYANAMID.

1,292,715.

Specification of Letters Patent.

Patented Jan. 28, 1919.

Application filed December 3, 1917. Serial No. 205,215.

To all whom it may concern:

Be it known that I, GEORGE E. Cox, a citizen of the United States, residing at Niagara Falls, in the county of Niagara and State of New York, have invented certain new and useful Improvements in Processes of and Apparatus for Making Calcium Cyanamid; and I do hereby declare the following to be a full, clear, and exact description of the invention, such as will enable others skilled in the art to which it appertains to make and use the same.

This invention relates to a process of and an apparatus for improving the grade of the product, and reducing the consumption of the raw materials in the manufacture of commercial calcium cyanamid and has for its object to accomplish these results in a simple and easy manner.

To these ends the invention consists in the novel steps and combinations of steps constituting the process all as will be more fully hereinafter disclosed and particularly pointed out in the claims.

Referring to the accompanying drawings, forming a part of this specification, the figure is a diagrammatic sectional view of a furnace suitable for carrying out the invention.

In order that the exact process may be the better understood, it is said:—

In the production of calcium cyanamid it has been common practice outside the United States to react upon calcium carbid with nitrogen at a suitable temperature, the carbid being contained in a foraminous vessel made of metal, paper, textile fabric, or a combination of these materials. The usual shape of this vessel has been generally cylindrical, the height being several times the diameter. This container is inserted in a gas tight nitrifying furnace of corresponding shape, the furnace being lined with suitable refractory and heat insulating material.

A free space usually surrounds the container between it and the lining of the furnace on all sides, and the top of the container is left open to permit of the easy dumping of its contents at the end of the operation. Nitrogen is admitted into the said free space and at the proper temperature reacts upon the heated carbid to form calcium cyanamid.

This reaction creates many gaseous products, which arise from impurities in the nitrogenous gas used, impurities in the calcium

carbid employed, and from such combustible materials as are used to line the container, or even to make up the body of the container. The gases thus formed may in turn react upon the carbid to change its character so that it no longer is capable of taking up nitrogen or at least to the extent it would have done, had it remained unaltered. This is particularly true of the exposed top surface of the carbid in the container; so that, after the completion of the nitrifying operation, one often finds upon the top of the solidified ingot of cyanamid, a layer of dust containing much less nitrogen than the bulk of the mass, or even none at all. This results not only in a loss of the valuable carbid, but also in producing a lowering of the grade of the cyanamid itself, and the production of a more or less dusty condition in the plant, at the places where the removal of the ingot from the container and its subsequent grinding and crushing takes place.

It is probably also true that a part of this decreased nitrification of the topmost portion of the mass of carbid is also due to excessive heat losses from the somewhat unprotected surface of the carbid mass. On account of operating conditions, it has not been customary to install as much heat insulation in the cover of the furnace as was provided, for instance, in the bottom, or around the sides thereof, and the mass of carbid not being thus protected even by the container on its top surface has suffered an excessive loss of heat.

I have found, first, that an increased fixation of nitrogen can be obtained if one inserts a slab of heat insulating material under the cover of the oven, but not in contact with the carbid container. I have found further, that if a similar slab of heat insulating material is made to accurately fit the container, and to rest directly upon the top of the mass of carbid, it protects this top surface, not only from loss of heat by radiation, but further, from contact with the above mentioned gases and moisture generated by the reaction, and I thus not only obtain a better fixation of nitrogen, but a materially reduced quantity of dust on top of the ingot. A suitable apparatus for carrying out the process is shown in the drawing in which "A" is a metal vessel forming the shell of the furnace, "B" the cover to the furnace, "C" the refractory and heat insulating lin-

ing of the furnace, "D" the nitrogen inlet, "E" the resistor for obtaining the necessary temperature for starting the reaction and passing through the furnace at "F" and "G" 5 which are electrically insulated joints.

"H" is the container for the carbid. "I" is the heat insulating slab for preventing loss of heat through the top of the furnace, and "K" is a slab resting upon the top of 10 the carbid, on the interior of said container, for preventing loss of heat and contact of the gaseous products of the reaction with the finely divided carbid "L." It is self evident that the slab "I" or the slab "K" may 15 be used either alone and independently of each other, or in combination as shown in the drawing. "M" represents any suitable space for the nitrogen, surrounding the container "H." "N" represents openings for 20 the admission of nitrogen to the mass of carbid "L," and "O" represents supports for the receptacle "H" adapted to preserve the space "M."

To illustrate the advantage of this process 25 and apparatus it is said:—I charged over a period of 15 shifts when manufacturing cyanamid on a commercial scale, one half of the cyanamid ovens in the usual manner without either the oven slab "I" or the container 30 slab "K," all in accordance with the old practice; the other half of the ovens were charged with carbid of the same composition and handled identically in the same manner with the exception that they were provided 35 with the slabs "K" substantially as shown resting on the carbid. As a result of this test on a large scale, under absolutely identical conditions, other than the slabs, "K," I found an increase of over 1% in the quantity 40 of nitrogen fixation by the carbid, a decrease of nearly 20% in the residual unfixed carbid in the cyanamid, and an increase of 2% in the efficiency with which the carbid was used, in favor of the furnaces using the slabs "K." 45 The average quantity of dust produced in the ordinary operation was 30 pounds per furnace operated. The dust produced in the furnaces provided with slabs "K" averaged only 5 pounds per furnace or a reduction of 50 25 pounds per operation in the amount of dust made in favor of the furnaces operated only with the slabs resting directly on the carbid.

In the case of the combined use of the two 55 slabs "K" and "I," I similarly obtained a greatly improved yield in quality of cyanamid, but it is not possible to present the numerical results in such a concrete form on account of the mutual influence of the two 60 slabs.

One of the principal advantages obtained by the use of a slab or slabs in the furnace is in the saving of labor in removing covers and slabs, because formerly the oven cover 65 could not be made of very light material as

it was subject to deterioration through the direct action of heat, but the furnace slabs "I" and "K" being made of kieselguhr or other similar light weight material, can be readily handled by a single individual. The 70 former practice requires two men and a crane for removing the necessarily heavier furnace covers, whereas one man can readily handle the lighter cover "B" and slabs "I" and "K." 75

It is obvious that those skilled in the art may vary the details of the process as well as of the apparatus without departing from the spirit of the invention, and therefore, I do not wish to be limited to the above disclosure except as may be required by the 80 claims.

What I claim is:—

1. The process of producing fixed nitrogen compounds which consists in reacting 85 upon a mass of calcium carbid with nitrogen while preventing a substantial portion of the evolved heat from escaping from the top surface of said mass, substantially as described.

2. The process of producing nitrogenous 90 compounds consisting in reacting on a mass of calcium carbid with nitrogen while substantially preventing the evolved gases from contacting with the top surface of said mass, substantially as described. 95

3. The process of making calcium cyanamid which consists in heating a mass of calcium carbid to a reacting temperature in the presence of free nitrogen; and substantially preventing the heat evolved from 100 escaping from the top surface of said mass while also preventing the evolved gases from coming into contact with said top surface, substantially as described.

4. In an apparatus for making calcium cyanamid, the combination of a perforated container for calcium carbid; a nitrifying closed furnace adapted to receive said container; and means to heat insulate the top surface of the carbid in said container, during the nitrifying reaction, substantially as 105 described.

5. In an apparatus for making calcium cyanamid the combination of a perforated container for a mass of calcium carbid; a 115 closed furnace for receiving said container; means to admit nitrogen into said furnace; means to provide a space between said container and the inside of said furnace; means to raise a portion of the carbid to the reacting temperature; and heat insulating means located at the top of said container to prevent the escape of heat from the top of said mass, substantially as described. 120

6. In an apparatus for making calcium 125 cyanamid the combination of a perforated container, for a mass of calcium carbid; a furnace for receiving said container; means to admit nitrogen into said furnace; means to provide a space between said container 130

and the inside of said furnace; means to raise a portion of the carbid to the reacting temperature; means to prevent the evolved gases from contacting with the top surface 5 of said mass; and heat insulating means located at the top of said furnace to prevent the escape of heat from the top of said mass, substantially as described.

7. In an apparatus for making calcium cyanamid the combination of a furnace lined 10 with a refractory material; a cover for said furnace; a heat insulating slab associated with said cover; and a perforated container provided with heat insulating means at its 15 top and adapted to hold calcium carbid located inside said furnace, substantially as described.

8. In an apparatus for making calcium cyanamid the combination of a closed furnace 20 lined with a refractory material; an additional cover for said furnace; a perforated

container adapted to hold calcium carbid located inside said furnace; and a heat insulating and gas excluding slab substantially closing said container, substantially as 25 described.

9. The herein described new article of manufacture comprising a perforated container 30 adapted to hold a mass of calcium carbid in a finely divided condition provided with means to admit nitrogen to said carbid; and also provided with a heat insulating, gas excluding slab of refractory material adapted to rest on the top of said mass, substantially as described. 35

In testimony whereof I affix my signature, in presence of two witnesses.

GEORGE E. COX.
